BICYCLE LIGHT

Viktor Schreckengost, Cleveland Heights, Ohio, assignor
to The Murray Ohio Manufacturing Co., Nashville, Tenn., a corporation of Ohio

Filed June 15, 1964, Ser. No. 80,397

Term of patent 14 years

(Cl. D48—24)

The fragmentary broken line showing of the bicycle is for illustrative purposes only.

I claim:

The ornamental design for a bicycle light, substantially as shown and described.
